UNITED STATES PATENT OFFICE

PIERO MARIANO SALERNI, OF SYDENHAM HILL, LONDON, ENGLAND, ASSIGNEE, BY
MESNE ASSIGNMENTS, TO ROLLS RAZOR (1927) LIMITED, OF LONDON, ENGLAND, A
COMPANY OF GREAT BRITAIN

DEVICE FOR SHARPENING SAFETY-RAZOR BLADES

Application filed August 1, 1925, Serial No. 47,627, and in Great Britain August 18, 1924.

The present invention relates to devices for sharpening safety razor blades, of the kind in which the blade is automatically rocked at the end of each stroke to reverse it and is 5 automatically caused to bear on the whetting or sharpening surface during the strokes, there being provision for automatic adjustment of the edge of the blade on the said surface considering said surface transversely 10 to the direction of the strokes, the blades dealt with being of the comparatively rigid type and approximately wedge-shaped in cross section in distinction to a flexible or wafer type of blade. By the term "wedge-shaped" it is to be understood that I include 15 all blades which are thicker at the back so that when they lie on a surface an imaginary straight line passing through the middle of the thickness of the back to the edge would 20 be at an angle to that surface and whether the blade be made entirely in one piece or the additional thickness at its back part be made by securing a part or parts thereto. In both 25 honing and stropping such approximately wedge-shaped blades, and particularly in honing, it is necessary or very desirable that the angle at which the edge of the blade is 30 presented to the whetting or sharpening surface be always the same and it is also advantageous that this angle shall be as small as possible. The main object of the present invention is to attain these advantages in safety 35 razor sharpening devices of the kind referred to.

35 In safety razor sharpening devices of the kind referred to the razor blade is connected to a carrier which is reciprocated over the whetting or sharpening surface and according to the said invention the connection devices are adapted to allow the blade to adjust 40 itself on the whetting or sharpening surface angularly in a direction from edge to back or vice versa, whereby as the blade is presented to the whetting or sharpening surface 45 it adjusts itself so that both its back part and edge bear thereon in a "floating" manner during the stroke. Consequently any variation in distance between the axis of the carrier and the whetting or sharpening surface either at 50 different parts of the same apparatus or in the one apparatus as compared with another intended to be similar in dimensions, the blade edge is always sharpened at the same angle and that angle is the most acute angle possible. The adjustment of the blade on 55 the whetting or sharpening surface is preferably of tilting or rocking character arranged to take place on a fulcrum a substantial distance from the back of the blade towards the edge and consequently to cause the pressure on the blade to be applied to that part. In some forms of devices for sharpening safety razor blades of the kind referred to as heretofore known the blade has been 60 removably connected to the carrier by means of a pin on the carrier engaging in a hole in the back of the blade in which hole the pin has a working fit. With this kind of connection the present invention may be conveniently embodied by providing that while the pin 65 has a working bearing at or near the bottom of the hole its diameter is smaller than the diameter of the hole or its width in the direction of the thickness of the blade from the bearing part of the pin outwardly, to afford room for 70 play. This relative difference in diameter may be conveniently provided by the hole having an increased diameter from the bearing part for the pin outwardly. The bearing part for the pin in the blade is preferably 75 about midway between the back and edge of the blade or as near the middle as feasible having regard to the thickness of the blade at that part. Thus the blade may tilt or rock 80 angularly on the inner end portion of the pin. To provide that the blade shall be locked on 85 the pin during use of the sharpening device an abutment or abutments may be provided on the pin at a suitable part thereof located or to be located within the hole in the blade, 90 say at a short distance from the outer end of the hole, and the hole is provided with a recess or recesses in its wall at that part to form an abutment or abutments for the outer side 95 or sides of the abutment or abutments on the pin the size of the recess or recesses being such that while the freedom of the tilting or rocking movement of the blade on the end of the pin is not interfered with by the abutments referred to yet they prevent the blade 100

leaving the pin in the reversal and whetting movements. In order to provide for the blade being engaged with pin and disengaged therefrom the abutment or abutments on the pin may project or be situated only in one direction transverse to the axis of the pin or project substantially less in that direction as compared with a direction at right angles thereto and the outer part of the hole 10 in the blade between the recess or recesses therein and the back of the blade may be of a slot-like or elliptical shape, its larger diameter being at right angles to and a little larger than the greatest diameter across the 15 abutment or abutments on the pin when the blade is on the pin in the sharpening position and the smaller diameter of the outer part of the hole is such that the abutment or abutments on the pin at the least dimension across 20 it or them or the portion between it or them can pass through it. The result of this provision is that the blade may be connected with the pin by placing the hole in the blade over the pin on the carrier while the blade is 25 at right angles to the axis of the carrier and then turning the blade through an angle of about 90° and the blade may be disconnected by reverse action.

In order that the said invention may be 30 better understood and carried into practice the preferred embodiment thereof is herein-after particularly described with reference to the accompanying drawings which illustrate by way of example an embodiment of 35 the invention in a known form of a razor sharpening device of the kind hereinbefore referred to.

Figure 1 of the said drawings is a fragmentary somewhat diagrammatic plan view 40 of the carrier for the blade in the razor sharpening device with the blade connected thereto. Figure 2 is a section taken on the line A, A Figure 1, showing some parts in side view, Figure 3 is a sectional view similar to 45 Figure 2 but showing the blade and the adjacent parts of the carrier in the position they adopt when the blade is being traversed over the sharpening surface, Figure 4 is a sectional view taken on the line B, B Figure 50 2, and Figure 5 is a sectional view taken on the line C, C Figure 2. The said sections Figures 4 and 5 only show the parts adjacent to the connection between the carrier and the blade. Figures 6, 7 and 8 are respectively 55 a face view, end view and detail in section on the line D in Figure 7 illustrating the guard member hereinafter described preventing also the edge of the blade striking the sharpening surface before the back part. 60 Figures 2-5 are drawn to a larger scale than Figures 1, 6, 7 and 8.

In the following description the parts of the said drawings are referred to by the letters marked thereon and the same letters indicate the same parts in all the figures.

The particular form of sharpening device in connection with which the invention is illustrated is that in which the blade is temporarily connected with a carrier consisting of a spindle carrying a toothed wheel at each side meshing with racks whereby the spindle is rotated as the carrier is reciprocated and the blade is connected with the carrier through the medium of a pin engaged in a hole in the blade, the said pin having a fork or yoke which engages the spindle of the carrier at a reduced part thereof so that the said spindle may rotate independently of the pin, a friction device being provided around the spindle, in the form of a sleeve of resilient material such as steel embracing the spindle with resilient pressure, the said pin being engaged in a hole in the said sleeve so that the sleeve and pin may turn together. In the said drawings *x* is the whetting or sharpening surface, *a* is the spindle of the carrier, *b*, *b* the said toothed wheels, *c* the pin provided at *d* with a fork or yoke engaging in the reduced part of the spindle at *e* and *f* is the sleeve of resilient material. *y* is the 90 blade and *z* is a part of the handle by which the carrier is reciprocated. The parts referred to may be taken to be parts of a device for honing and stropping such as described in United States Patent 1,512,058 95 and in the accompanying drawings the parts are shown as arranged for honing. As the carrier of the device is reciprocated the spindle rotates and due to the friction of the sleeve *f* on the spindle *a* the blade is caused 100 to bear against the whetting or sharpening surface and at the end of a stroke the said friction is sufficient to reverse the blade and cause it to strike the whetting or sharpening surface at the beginning of its next stroke in the direction opposite to that of its previous stroke. These features are no part of the present invention which relates as should be understood from the description herein-before given, to the connection between the 110 carrier and blade to allow the blade to adjust itself and bear on the whetting or sharpening surface in the floating manner herein-before referred to. To this end in the embodiment illustrated the end of the pin *c* is hemispherical and has a working bearing in the bottom of the hole *g* in the blade but at the other parts the said hole has as shown a diameter substantially larger than that of the pin to afford room for play between the 115 pin and the blade and to enable the end of the pin *c* to cause the blade to bear on the whetting or sharpening surface both at its back and edge parts notwithstanding any variation there may be from time to time or in 120 different apparatus in the distance between the axis of the spindle *a* and the whetting or sharpening surface, the blade thus tilting or rocking angularly as may be necessary on the inner end portion of the pin as the blade 125

is brought on to the whetting or sharpening surface and while the blade is being caused to bear on that surface during a stroke if there be any variation in that surface. The blade may also turn slightly on the pin to adjust itself on the whetting or sharpening surface considering said surface transversely to the direction of reciprocation of the carrier although this feature so far as the edge of the blade is concerned, is not novel in itself. It is preferred that the inner end of the pin shall be hemispherical and the bottom of the hole of corresponding shape so that the blade may tilt or rock in the required direction or directions on the end of the pin after the manner of a ball joint, but the end of the pin may be of other forms as for instance conical, the point having a bearing at the apex of a conical shape of shallower angle given to the bottom of the hole.

In order to provide that the blade shall be locked on the pin *c* during use of the sharpening device abutments *h*, *h* are provided on the pin at such a part that they are located and free to play to a limited extent in the circular recess *i* a little distance from the back of the blade and of a larger diameter than the outer end of the hole *g* in the blade that is that part of it which constitutes the passage between the said recess *i* and the back of the blade through which the pin is passed and in which it is partly located. The abutments *h*, *h* are formed by forming flats at opposite parts of an annular shoulder originally so formed on the pin *c*. The abutments *h*, *h* do not interfere with the freedom of the blade to tilt or rock to a limited extent on the end of the pin as described but nevertheless prevent the blade leaving the pin during the whetting operation. When the blade is being honed it is caused to pass over and bear on the whetting or sharpening surface with its edge foremost by the end of the pin *c* working and bearing on the bottom of the hole in the blade without interfering with any tilting or rocking of the blade and therefore there is no tendency for the blade to leave the pin during the stroke but nevertheless an abutment such as those at *h*, *h* is necessary at least to prevent the blade leaving the pin during the reversal movement of the blade. In stropping a blade it is caused to pass over the stropping surface with its back foremost and in this case although the end of the pin *c* puts pressure on the blade, the blade is drawn over the stropping surface through the medium of the abutments *h*, *h* bearing against the outer wall of the recess *i* and they also prevent the blade leaving the pin during reversal movement of the blade. In order to provide for the blade being engaged with the pin *c* and disengaged therefrom the abutments *h*, *h* are opposite one another leaving a portion between them of less width

in a direction across the sharpening surface and the outer end of the hole in the blade or the passage between the recess *i* and the back of the blade is of greater diameter in a direction across the sharpening surface than in a direction at right angles thereto the smaller diameter of that part of the hole or the passage being slightly greater than the width or diameter of the portion between the abutments *h*, *h* and greater than the diameter of the outer part of the pin *c* but smaller than the dimension across the abutments *h*, *h* so that although there is freedom of play at that part between the blade and the pin yet the abutments *h*, *h* prevent the blade being removed from the pin when the parts are in the positions illustrated. The greater diameter or width of the passage referred to is as shown in Figure 4, a little larger than the dimension across the abutments *h*, *h*. It will therefore be realized that the connection between the pin and a blade is of a bayonet joint-like character that is the hole in the blade is engaged with the pin *c* by being passed thereover, while the blade is in a position at right angles to the axis of the spindle *a* and then when the abutments *h*, *h* are within the recess *i* the blade is turned through about 90° into the position illustrated in the drawings. This bayonet joint-like connection between the blade and the carrier does not however in itself form any part of the present invention.

It is convenient that the bearing of the inner end of the pin *c* in the hole in the blade should be a considerable distance from the back part as illustrated and this distance may suitably be between one third and one half the distance from the back of the blade to the edge or as near the middle from back to edge as feasible having regard to the thickness of the blade so that the pressure of the end of the pin is applied to such part of the blade that the edge of the blade is caused to bear on the whetting surface with a desirable degree of pressure as well as the back of the blade.

It will be seen by examining Figure 3 which shows the blade and parts in the position they take up and retain during the stroke that there is substantial facility for adjustably tilting or rocking movement of the blade on the end of the pin *c* so that the blade bears on the whetting or sharpening surface both at its back part and edge part at all times during the stroke notwithstanding any irregularities in the surface or variation of the distance of the axis of the spindle *a* from the whetting or sharpening surface; consequently the angle at which the edge of the blade is presented to the whetting or sharpening surface is always the same and that angle is as small as possible.

It is desirable to provide that when the blade is being presented to the whetting or

- sharpening surface at the end of the reversal movement the edge of the blade should not first strike the whetting or sharpening surface but that the back of the blade should do so. This may be provided for by providing on the blade near its edge a member which may be turned to either side of the edge with slight resistance. If therefore when the blade is approaching the whetting or sharpening surface the edge part is nearer thereto than the back part, the said member first strikes the whetting or sharpening surface causing the blade to tilt so that the back part bears on the whetting or sharpening surface before the pressure is sufficient to bring the edge into contact with the surface against resistance of the member to movement relatively to the blade. Such a member may be functionally constituted by a guard member to prevent injury to the fingers and/or a guard to act as such in shaving such as illustrated in Figures 6, 7 and 8 in which *j* is the guard member pivoted to the blade at *k*, *k*, so that it may be moved from one side of the edge of the blade to the other. The arms of the guard member are slightly resiliently displaceable from the ends of the blade and one arm carries a pin working in a recess *l* of greater diameter than the pin to limit the movement of the guard member and at the other arm of the guard member is the device to retain the member temporarily in position to one or other side of the blade, the device also causing the latter part of the movement of the guard member in either direction to take place automatically. This device consists of a sphere *m* arranged in a recess in the blade and having some freedom of lateral movement therein in a direction across the thickness of the blade and a projection *n* on the end of the arm of the guard member which projection rides over the outer portion of the sphere against the resilience of the arm when the guard member is moved towards and past the edge of the blade. The projection *n* is formed of a steel sphere secured in a recess in the arm by pressing the adjacent metal around the sphere.
- The invention is not limited to the form or arrangement and details described and illustrated as these may be varied very substantially without departing from the spirit of my invention.
- What I claim and desire to secure by Letters Patent of the United States is:—
1. In combination in a safety razor blade sharpening device, sharpening material, a reciprocable carrier for the blade, means to automatically rock the blade at the end of each stroke to reverse it, means to cause the blade automatically to bear on the sharpening surface of said material during the stroke and connection devices between the carrier and the razor blade permitting of adjustment of the blade edge on the sharpening surface
  2. In combination in a safety razor blade sharpening device, sharpening material, a reciprocable carrier for the blade, means to automatically rock the blade at the end of each stroke to reverse it, means to cause the blade automatically to bear on the sharpening surface of said material during the stroke, and a pin on the carrier engaging in a hole in the back of the blade, the said pin having a working bearing at or near the bottom of the hole and having a diameter smaller than the width of the hole in the direction of the thickness of the blade, from the bearing part of the pin outwardly, to afford room for sufficient angular play between the pin and the blade to enable the back part of the blade as well as its edge part to adjust themselves on the sharpening surface without restraint by the said pin.
  3. In combination in a safety razor blade sharpening device, sharpening material, a reciprocable carrier for the blade, means to automatically rock the blade at the end of each stroke to reverse it, means to cause the blade automatically to bear on the sharpening surface of said material during the stroke, a pin on the carrier engaging in a hole in the back part of the blade, the said pin having a working bearing at or near the bottom of the hole and having a diameter smaller than the width of the hole in the direction of the thickness of the blade, from the bearing part of the pin outwardly, to afford room for sufficient angular play between the pin and the blade to enable the back part of the blade as well as its edge part to adjust themselves on the sharpening surface without restraint by the said pin, and an abutment or abutments on the said pin to engage in a recess or recesses in the hole in the blade to prevent the blade leaving the pin during operation of the sharpening device.
  4. In combination in a safety razor blade sharpening device, sharpening material, a reciprocable carrier for the blade, means to automatically rock the blade at the end of each stroke to reverse it, means to cause the blade automatically to bear on the sharpening surface of said material during the stroke, a pin on the carrier engaging in a hole in the back part of the blade, the said pin having a working bearing at or near the bottom of the hole and having a diameter smaller than the width of the hole in the direction of the thickness of the blade, from the bearing part

of the pin outwardly, to afford room for sufficient angular play between the pin and the blade to enable the back part of the blade as well as its edge part to adjust themselves on the sharpening surface without restraint by the said pin, and an abutment or abutments on the said pin to engage in a recess or recesses in the hole in the blade to prevent the blade leaving the pin during operation of the sharpening device, the said abutment or abutments constituting a substantially radial projection or projections and the opening part of the hole having a larger diameter in one plane than the diameter in a plane at right angles thereto in order to afford for a bayonet joint-like connection between the blade and carrier.

5. In combination in a safety razor blade sharpening device, sharpening material, a carrier for the blade, said carrier being reciprocable in a definite path above said material, means to automatically rock the blade at the end of each stroke to reverse it, means to cause the blade to automatically bear on the sharpening surface of said material during the stroke, and connection devices between the carrier and the razor blade adapted to allow the blade to adjust itself on the sharpening surface so that both the back part and edge 25 part of the blade bear on the said surface through the stroke without restraint by the said connection devices notwithstanding the definite path of reciprocation of the carrier.

PIERO MARIANO SALERNI.
